OIL BURNER

Herschel C. Faulkner, Birmingham, Ala., assignor of one-half to J. W. Love, Monroe, N. C.

Application July 11, 1938, Serial No. 218,598

4 Claims. (Cl. 158—91)

This invention relates to hydrocarbon burners, particularly to oil burners of that type embodying a burner member through which the oil is fed to be burned on its surface, and an air manifold discharging heated air downwardly onto the burner member, and has for an object the provision of apparatus of the character designated which shall include an improved burner member with fuel discharge orifices so directed as to afford the highest efficiency in preheating the air for combustion, and which shall also afford an improved surface for burning the fuel.

A further object of my invention is to provide a hydrocarbon burner of the character designated in which there is embodied improved means for regulating the flow of air through the manifold.

A still further object of my invention is to provide a hydrocarbon burner which shall be simple and economical of design, and reliable in operation.

Briefly, my invention comprises a burner of the type in which the fuel is burned on the surface of a burner member which is supplied with a downward current of heated air for combustion, through a manifold. The manifold in this type of burner is more or less heated by the surrounding flame, and in my improved burner I provide fuel discharge orifices which are directed toward the base of the manifold whereby the flame is concentrated on the lower part thereof and improved preheating results. I have also discovered that combustion in burners of this type may be improved by providing means to admit a regulated amount of surrounding gases to the manifold between its regular intake and the discharge thereof. This is particularly true where the burner is located in a stove or furnace connected to a flue providing an especially strong draft. I also provide an improved burner member with means affording an even film of oil over the surface whereby improved combustion results.

The above mentioned, and other important features of my invention, are illustrated in the accompanying drawing forming a part of this application, in which

Fig. 1 is a plan view partly in section of my improved burner taken along the line I—I of Fig. 2;

Fig. 2 is a sectional elevation taken along the line II—II of Fig. 1;

Fig. 3 is an enlarged elevational view of the burner member of my improved burner viewed in the direction of the arrows III—III of Fig. 1; 55 and

Fig. 4 is a fragmentary sectional view taken along the line IV—IV of Fig. 1.

Referring to the drawing for a better understanding of my invention, my improved oil burner comprises a base 10, which may be of cast iron, formed with an outer flange 11. On the bottom of the base, I provide a plurality of bars 12 having longitudinal slots 13 therein which are adjustably held in place beneath the base 10 by means of studs 14 passing through the slots, the purpose of the slotted bars being to engage the side walls or supports in a stove or furnace (not shown) to support the burner in operation in a manner well understood. The bars 12 being adjustable, the base 10 is adapted to be installed in various sizes of stoves and furnaces.

The base 10 has formed therein spaced air openings 16 and 17, enlarged near their upper ends to provide shoulders 18 and 19. An air manifold 21 is disposed centrally above the base and has downwardly extending arms 22 and 23 fitting into the openings 16 and 17 with their ends resting on the shoulders 18 and 19 whereby to form a continuous passage upwardly through the manifold. The manifold has a downwardly directed discharge opening 24 therein, through which the air passing upwardly through the arms 22 and 23 is discharged. It will also be noted that the arms 22 and 23 are each curved round and inwardly at 26 and 27 so as to provide a minimum of resistance to the air flow on its way to the discharge 24 where the air from the two arms is commingled. Reinforcing rings 28 and 29 may be provided around the lower end of the arms 22 and 23 of the manifold 21 where they connect to the openings 16 and 17. A reinforcing rib 25 joins the upper, downwardly curved portions of the manifold arms 22 and 23.

Formed in the base, centrally thereof, is a receptacle 31 having a groove 32 therein in which there is placed asbestos wicking 33, or other suitable non-combustible porous material to collect oil and be ignited when starting the burner. Centrally of the receptacle 31 and directly beneath the discharge opening 24 of the manifold is a conical burner member 34 having, near its upper end, a horizontal shoulder 36 so as to provide a reduced upper conical portion 37. Extending spirally about the burner member 34 and beginning at the horizontal shoulder 36 is a grooved shoulder 38 which terminates at the bottom in a deeper groove 35 surrounding the base of the burner member. Oil for combustion is supplied upwardly through the center of the burner member from a pipe 39 through a central passage 50

41. The upper end of the passage 41 terminates just above the level of the shoulder 36, at which point there are provided a pair of intersecting diametral fuel discharge orifices 42 and 43, which 5 are directed toward the depending arms 22 and 23 of the manifold 21. The passages 42 and 43 describe an acute angle of approximately 40°, though this may be varied from somewhat, the purpose being to direct the major portion of the 10 flame in burning toward the manifold arms and thus provide improved preheating of the air for combustion.

In starting the burner, fuel is supplied through the pipe 39 and discharges through the fuel discharge orifices 42 and 43. When the burner is cold the oil flows down the conical burner member 34 following the spiral groove in the shoulder 38 in a regular path so that there is no accumulation of oil on the burner member in such a way 15 that it would burn incompletely and cause smoke. Oil may fill the groove 35 and the excess oil run over into the receptacle 31. A drain pipe 40 connects to an opening 45 extending upwardly through the bottom of the base so that only 20 sufficient oil is allowed to gather in the receptacle 31 to start the burner in operation. The oil is ignited on the wicking 33 and immediately begins to heat the manifold 21. As soon as the manifold becomes heated, it induces a draft of 25 air through the arms 22 and 23 and the air, preheated in the manifold, is discharged downwardly on to the burner member 34. When the burner member 34 is heated sufficiently, it vaporizes the oil in the groove 35, which mixes with 30 the heated air and ignites. From then on the oil is vaporized on the heated burner member as it is discharged through the orifices 42 and 43 and the burner operates like a gas burner with vaporized oil. When the air discharged through the 35 opening 24 strikes the upper end of the conical burner member 34, it mixes with the oil being discharged through the diametral openings 42 and 43, and the spiral protuberance 38 on the burner member causes the air coming in contact therewith to assume a spiral path and effectively burn 40 the oil.

My improved burner is adapted to be fitted into and form a part of various stoves, furnaces and boilers with various types and sizes of flues having more or less intense draft. The burner is accordingly designed to operate with a minimum of draft and, as designed, when associated with certain stoves or furnaces, the draft might be too intense through the manifold 21 for the best combustion. I have accordingly provided a means 50 for regulating the air supply through the manifold to suit whatever condition may be encountered. This is accomplished by providing openings 44 in the depending arm 22, above the base, and similar openings 46 in the depending arm 23. Over the openings 44 and 46 I place check draft members 47 and 48 which are adjustable by means of screws 49 and 51 to admit more or less air or surrounding gas into the manifold arms 55 above the base, thus reducing the flow of air through the base openings 16 and 17. The set screws 49 and 51 are set and adjusted when the burner is first installed and require no further attention as long as it is in service. My improved burner is thus adapted to be installed and operated under widely varying conditions of 60 draft.

My improved burner is equally efficient in burning gas, as in burning oil, although it is primarily designed as an oil burner. From the fore-

going it will be apparent that I have devised an improved hydrocarbon burner which includes improved means for insuring complete combustion of the fuel and for regulating the draft.

While I have shown my invention in but one 5 form, it will be obvious to those skilled in the art that it is not so limited, but is susceptible of various changes and modifications, without departing from the spirit thereof, and I desire, therefore, that only such limitations shall be placed 10 thereupon as are imposed by the prior art or as are specifically set forth in the appended claims.

What I claim is:

1. In a hydrocarbon burner, a base having spaced air openings and a central conical burner 15 member providing a burning surface, an air manifold having downwardly extending air intake arms connected to the openings in the base and having a downward discharge opening above the burner member, a horizontal shoulder on the 20 burner member near the top thereof, means at the shoulder forming horizontally disposed fuel discharge orifices in the burner member directed toward the lower part of the manifold arms, means to supply fuel to the burner member, and 25 means to admit a predetermined amount of combustion products to each of the manifold arms at a point between the base and the junction of the arm whereby air so admitted is highly preheated before striking the burner member. 30

2. In a hydrocarbon burner, a base having spaced air openings and a central conical burner member providing a burning surface, an air manifold having downwardly extending arms connected to the openings in the base and having 35 a downward discharge opening above the burner member, a horizontal shoulder on the burner member near the top thereof, means at the shoulder forming horizontally disposed fuel discharge orifices in the burner member directed 40 toward the manifold arms, means to supply fuel to the burner member, and adjustable combustion products admission means in the manifold arms at a point above the base and between the lower ends of the arms and the downward discharge opening. 45

3. In a hydrocarbon burner, a base having a pair of spaced air openings, an air manifold having downwardly extending arms connected to the openings in the base, the upper portions of said arms being curved inwardly and downwardly toward a central downward discharge opening where the air in said arms is commingled, a conical burner element providing a burning surface disposed centrally beneath the discharge opening and having horizontally disposed slightly diverging fuel discharge orifices therein effective to direct the major portion of the burning fuel toward the lower ends of the manifold arms, means to supply fuel upwardly through the burner element to be discharged through the orifices, and adjustable inlets on each of said arms between the lower ends thereof and the point of inward and downward curvature to admit predetermined amounts of highly heated combustion products to said manifold. 55

4. In a hydrocarbon burner, a base having a pair of spaced air openings, an air manifold having downwardly extending arms connected to the openings in the base, the upper portions of said arms being curved inwardly and downwardly toward a central downward discharge opening where the air in said arms is commingled, a reinforcing rib joining the inwardly and downwardly curved portions of the manifold arms, a conical 70

burner element disposed centrally beneath the discharge opening of the manifold, a shoulder near the upper end of the burner element, means forming horizontally disposed slightly diverging fuel discharge orifices at the shoulder adapted to direct the major portion of the fuel toward the lower ends of the manifold arms, a spiral grooved shoulder on the burner element from the horizontal shoulder to the base thereof, means form-

ing a groove at the base of the burner element, means to supply fuel centrally and upwardly through the burner element to be discharged through the orifices, and adjustable inlets on each of said arms between the lower ends thereof and the point of inward and downward curvature to admit predetermined amounts of highly heated combustion products to said manifold. 5
